UNITED STATES PATENT OFFICE.

HORACE M. KEITH, OF COMMERCE, MICHIGAN.

MACHINE FOR SEPARATING AND ASSORTING POTATOES.

SPECIFICATION forming part of Letters Patent No. 448,434, dated March 17, 1891.

Application filed September 22, 1890. Serial No. 365,785. (No model.)

To all whom it may concern:

Be it known that I, HORACE M. KEITH, a citizen of the United States, residing at Commerce, in the county of Oakland and State of Michigan, have invented new and useful Improvements in Machines for Separating and Sorting Potatoes, of which the following is a specification.

I have invented an improved machine for separating potatoes as they are dug from the hills with the vines and the earth, and in which the cleaned potatoes are assorted into grades. In the construction of the machine provision is made for operating the separating-platform by hand or by the feet, or by both; and the machine is designed with special regard for cheapness of construction, for durability, and for satisfactory work, as I will now describe in connection with the accompanying drawings, and will point out the precise improvements in the claims concluding this specification.

Referring to the drawings, Figure 1 shows my improved potato-separator in perspective. Fig. 2 is a vertical longitudinal section of the same. Fig. 3 is a vertical transverse section taken through the foot-operated lever, and Fig. 4 shows in top view the separating-platform and its connected foot and hand operating-levers and their relation to the operator's seat, and Fig. 5 is an end view of the discharge separating-platform.

The frame consists, essentially, of two long sills *a a*, an axle-beam *b*, secured crosswise to the sills near their ends, the other ends of the sills being connected by a cross-piece *c*, the sills being parallel and placed close together to run between two rows of potatoes, and the machine is guided and turned by shafts, so that the horse, hitched between them by a whiffletree to the front cross-piece *c*, walks between two rows. The axle extends beyond the sills and has carrying-wheels *d d*, which run on outer sides of the two adjacent rows. At the junction of the axle and the sills I firmly secure at the outer sides of the latter uprights *e e*, and at the other ends of the sills, at the junction of the cross-piece *c*, two like uprights *e' e'* are firmly secured, and these uprights are connected by cross-bars *ff* at their upper ends. At each side these uprights are connected by boards or bars *gg*, which extend

beyond the uprights *e' e'* and form the shafts *g' g'*, by which the machine is turned or guided. Below these shaft-bars two other bars *hh* are secured to the four uprights, and between these uprights the separating-platform is suspended about in a plane with the shaft-bars. This separating-platform is composed of two side timbers *ii*, between which a bottom screen *j* is formed by longitudinal slats placed so as to screen and separate the earth from the potatoes, and is of a length about two-thirds that of the side timbers with that end next the shaft-bars closed. At the other end of this screen I secure between the side timbers two parallel bars *kk*, which join the side timbers by flaring ends *k' k'* at the end of the screen *j*, so as to leave spaces *ll* between the side timbers and the inner bars. Between these inner bars a coarse screen *m* is formed by slats *n* on a plane with the screen *j*, from which latter the potatoes pass upon the coarse screen and are sorted, the young or smaller potatoes passing through it, while the larger potatoes pass off at the end. These inner bars extend below the side timbers, and between them a lower second finer screen *p* is formed to receive the sorted potatoes; but it will be noticed that this second screen is of less length and is shorter than the upper sorting-screen, for a purpose to be presently stated.

The separating-platform is suspended between the uprights by rods *q*, pivotally connected to the side timbers and to the uprights, so that the receiving end of the platform, which is next the shaft-bars, can be adjusted vertically to incline it to give the potatoes the proper discharge movement over and from the screens. The front uprights *e' e'* are for this purpose provided with holes *q'*, into which to set the rods higher or lower to give the operating-platform more or less inclination.

As a means of shaking the platform, I provide a hand-lever *r*, pivoted at its lower end to one of the side bars *h* and to the side timber of the platform, so that it can be reached and vibrated by the operator from a seat *s*, placed upon the side bars against the uprights *e e* above the platform. I also provide for shaking the separating-platform by means of the feet of the operator, so that

when he tires using the hand-lever he can use his feet, leaving both his hands free to remove the vines from the screen as they are fed down toward him. For this purpose I 5 provide a foot-lever *t*, placed across and above the sills upon a rock-bar *u*, journaled in the axle and in a cross-bar *v*. A bell-crank lever is pivoted to the other side bar *h*, and its slotted ends are connected, the one *h'* to the 10 side timber of the platform and the other *h''* to one end of the foot-lever, so that the operator's legs, standing down in the spaces *ll*, with his feet upon each end of the foot-lever, can rock it, and thus vibrate the bell-crank 15 lever, and through it vibrate the separating-platform. In this shaking of the platform it is subjected to sudden knocks by means of stops *x*, projecting from the side timbers so as to strike against the uprights *e e* on the 20 backward and upward swinging movement of the platform, giving a sudden jar to the platform, causing the potatoes to jump up and back and the earth to pass down through the screen. That end of the bell-crank lever 25 which is connected to the foot-lever is preferably extended beyond such connection to receive a weight *y*, which I find greatly increases the leverage force in throwing the platform against its stops and shaking up the 30 potatoes and earth and throwing them slightly to the front.

On the ends of the sills which project back of the axle I place a box, which extends between the carrying-wheels with its inner side 35 against the uprights *e e*, and I divide this box into two separate compartments *A B*, which extend its length, by means of a removable partition *C*, so that the inner compartment will be directly under the discharge end of 40 the lower short screen of the separator-platform, while the upper longer sorting-screen of this platform will discharge into the outer compartment. Both of these compartments may be permitted to fill with the sorted potatoes, and the larger ones removed first therefrom by turning down the hinged back *D* upon the ends of the sills, as shown by dotted lines in Fig. 2, and then taking out the partition *C*. The rear compartment may, however, 45 be used to hold baskets, which can be placed under the discharge end of the upper sorting-screen and shoved to one side as they are filled, so that the box can carry one compartment to be filled with the small potatoes and 50 a number of baskets to be filled with the larger potatoes as the operation of digging and cleaning progresses in the field.

A short screen *E* may be secured upon the side timbers of the platform above the main 55 screen to receive the potato-hills as they are shoveled thereon for the purpose of retaining the vines, and allow the potatoes and earth to fall through them upon the main screen, as shown in dotted lines in Fig. 1 and in full lines in Figs. 2 and 4. I may also provide the receiving-compartments *A* and *B* with screen-bottoms, so that any dirt which may

pass with the potatoes into these compartments will drop through the slotted bottoms of these compartments. 70

The sills are placed near together, as stated, so that they will run between and not be in the way in digging the hills, and two or three rows may be dug on each side of the screen and from sixteen to twenty-five hills may be 75 thrown into the screen at each stop.

It will be seen that the shaking platform is suspended quite low down in the frame, and that the operator's seat is placed low down on the frame, so that a canopy may be supported 80 upon the uprights as a cover for the operator, who sits with his feet upon the foot-lever and with his hands free to catch and throw out any vines or stones that may be moved with the potatoes down the screen, which he sits 85 facing. This construction also gives the advantages of permitting him to use a hoe or rake or fork to facilitate the separation of the potatoes and to remove the vines, and he can use his hands for cleaning the potatoes as they 90 pass upon the narrow screen, while he uses his feet to shake the platform.

I claim as my improvement—

1. In a machine for separating and sorting potatoes, the shaking platform having the 95 short top vine-receiving screen *E*, the separating-screen *j*, the short end sorting-screen *m*, and the short under-end screen *p* of different size openings, in combination with the carrying-frame having a transverse box-receptacle 100 extending beyond each side of the frame and having compartments arranged to receive the potatoes from the short end screens, as shown and described.

2. In a machine for separating and sorting 105 potatoes, the combination of a separating-platform, a carrying-frame therefor, a seat upon said frame, a rocking foot-bar beneath the platform, and a bell-crank lever pivoted to said frame, to the platform, and to said 110 foot-bar, for the purpose stated.

3. In a machine for separating and sorting potatoes, the combination of a separating-platform, a carrying-frame therefor, a seat upon said frame, a rocking foot-bar beneath 115 the platform, a bell-crank lever pivoted to one side of said frame, to one side of said platform, and to one end of said foot-bar, and a hand-lever pivoted to the other side of said frame and to said platform, for the purpose 120 stated.

4. In a machine for separating and sorting potatoes, the shaking platform having the separating-screen *j*, the inside boards *k k*, forming the side spaces *ll* within the platform, the coarse and fine screens *m p* between the inside boards, one above the other and the upper one on the same plane with the said screen *j*, in combination with a suitable box-receptacle for the sorted potatoes, and means 125 for longitudinally shaking said screens, consisting of a foot-lever *t*, a bell-crank lever connecting said foot-lever, the shaking platform, and the frame, as shown and described.

5. In a machine for separating and sorting potatoes, the combination of the frame, the seat thereon, the shaking platform having the side stops α and the side spaces ll , the foot-lever t below the platform, and a bell-crank lever connecting the said foot-lever with the platform and the frame and having its foot-lever connected end weighted, for the purpose stated.
- 10 6. In a machine for separating and sorting potatoes, the combination of the frame constructed with sills, the wheel-supported axle upon the rear ends of the sills, the uprights and the shaft-bars secured thereto, the sepa-

rating-platform suspended between said uprights, a transversely-arranged box of two compartments upon the rear ends of said sills, a seat upon the frame, a foot-lever arranged beneath the platform and connected to operate said platform, and stops α upon the latter, as shown and described.

In testimony whereof I have hereunto set my hand in the presence of two subscribing witnesses.

HORACE M. KEITH.
